To all whom it may concern:

Be it known that I, WILLIAM GORMAN, of New Haven, in the county of New Haven, and State of Connecticut, have invented a new Design for Shelf-Bracket; and I do hereby declare the following, when taken in connection with the accompanying drawing, to be a full, clear, and exact description of the same, and which said drawing constitutes part of this specification, and represents a side view.

This invention relates to a design for a shelf-bracket, and consists of two arms or braces, at right angles to each other, the one supported from the other by a tracery of vine-work of a Gothic pattern, the branch therefrom forming a circle in the centre, with a leaf extending toward the end of either arm.

Having fully described my invention, What I claim as new, and desire to secure by Letters Patent, is—
